DESIGN FOR A TELEPHONE DESK UNIT

Clifford E. Erickson, Chicago, Ill., assignor to
Kellogg Switchboard & Supply Company, Chi-
cago, Ill., a corporation of Illinois

Application April 19, 1946, Serial No. 128,801

Term of patent 14 years

(Cl. D26—14)

To all whom it may concern:

Be it known that I, Clifford E. Erickson, a citizen of the United States of America, a resident of Chicago, county of Cook, and State of Illinois, have invented a new, original, and ornamental Design for a Telephone Desk Unit, of which the following is a specification, reference being had to the accompanying drawing, forming a part thereof, in which

Fig. 1 is a side view of the telephone desk unit, showing my new design;

Fig. 2 is a rear view of the same;

Fig. 3 is a front view;

Fig. 4 is a top plan view; and

Fig. 5 is a view in perspective.

I claim:

The ornamental design for a telephone desk unit, substantially as shown.

CLIFFORD E. ERICKSON.
